BINDER BAR AND HINGE LUG THEREFOR

George W. Newman, St. Louis, Mo., assignor to
 Loose Leaf Metals Company, a corporation of
 Missouri

Application March 30, 1934, Serial No. 718,111

4 Claims. (Cl. 129—12)

The invention relates to binder bars for loose leaf binders of the post type, and to hinge lugs therefor.

The objects of the invention are to provide a bar having apertures for engagement by the feet of a hinge lug, and a one-piece hinge lug having integral feet adapted to enter such apertures and be clinched therewithin.

In the accompanying drawing showing the preferred form of the device and the manner of attaching the hinge lug to the bar,

Fig. 1 is a view in perspective of a pressure bar of a loose leaf binder equipped with the improved hinge lugs;

Fig. 2 is a view in perspective of the lug and a portion of the bar, the parts being shown separately; and

Fig. 3 is a sectional view on the line 3—3 of Fig. 1.

The binder bar 10 is of ordinary construction, being made of sheet metal folded to form a flattened tube, its side margins being brought into contact with each other but without being secured together except by means of the improved hinge lug. The hinge lug is formed of a piece of sheet metal approximately rectangular in shape, its middle portion being bent to form a tube 11, providing a hinge pin socket 12, the two side portions of the sheet being continued radially and in contact to form a shank portion 13 of suitable length, and then spread laterally, as at 14, and then bent toward each other to form attaching feet 15, the intermediate portion of the side margins of the plate being cut away.

To provide for the attachment of the hinge lug to the tubular bar 10, the latter is apertured, as shown at 16, to receive the feet 15. These apertures flare slightly at the inner face of the tube wall, as shown at 17. The feet 15 having been inserted through the apertures 16, are bent toward each other, as shown at 18, and by means of a suitable tool are compressed by a swaging

action into the flaring inner ends 17 of the apertures 16, filling them and fixedly securing the lug to the bar. The swaging operation tends to draw together the edges of the sheet of which the bar 10 is formed, and the two hinge lugs 5 stiffen and strengthen the bar.

While the hinge lugs are shown as attached at the seam edge of the bar, they may, if desired, be attached at the closed edge, the stiffening and strengthening advantage referred to being sacrificed.

I claim as my invention—

1. A hinge lug formed of a piece of sheet metal folded along a median line to form a pintle eye, the side portions of the sheet being extended 15 radially and in juxtaposed relation to form a suitable shank, and then spread apart and rebent near their margins to form approximately parallel feet, the side margins of the sheet being notched to provide a plurality of feet.

2. In combination, a binder bar of sheet metal having the form of a flattened tube, the margins of the sheet meeting at one edge of the tube and being slotted, the inner ends of the slots flaring, 25 and a hinge lug formed of sheet metal and having integral feet projecting through the named slots and swaged to fill such slots.

3. In combination, a binder bar of sheet metal having the form of a flattened tube, the margins 30 of the sheet meeting at one edge of the tube and being slotted, the inner ends of the slots flaring, and a hinge lug formed of sheet metal and having integral feet projecting through the named slots and having their inner ends bent toward 35 the tube seam and being swaged to fill such slots.

4. In combination, a binder bar formed of a sheet of metal bent to form a flattened tube having an open seam and companion apertures on opposite sides of the seam, and a one-piece hinge 40 lug having feet projecting through the apertures and clinched against the inner face of the tube.

GEORGE W. NEWMAN.
